LOCK FOR COIN BANKS

Filed Nov. 27, 1926

Inventor
Fred Salinger
by Watson E. Coleman
his Attorney

UNITED STATES PATENT OFFICE.

FRED SALINGER, OF PHILADELPHIA, PENNSYLVANIA.

LOCK FOR COIN BANKS.

Application filed November 27, 1926. Serial No. 151,133.

This invention relates to small savings banks or coin banks such as used in saving coins for banking purposes and particularly to the lock thereof.

5 The general object of the present invention is to provide a lock for a savings bank of this character which is very simple, which is relatively cheap, but which is thoroughly effective for the purpose intended.

10 A further object is to provide a locking device for those banks which consists of two telescopic sections, the locking device acting to prevent the separation or withdrawal from or with relation to each other.

15 My invention is illustrated in the accompanying drawings wherein:—

Figure 1 is a vertical sectional view through a bank of this character having my improved lock attached thereto and taken on the line 20 1—1 of Figure 2;

Fig. 2 is a top plan view of the bank;

Fig. 3 is a side elevation thereof;

Fig. 4 is an elevation of the key.

Fig. 5 is a top plan view of the post.

25 Referring to these drawings 10 designates one section of the bank and 11 the opposed section thereof. The section 10 is provided with a base 12 having a bead or flanged connection 13 to the wall of the section 10. Ex- 30 tending upward through the bottom 12 is a locking post 14, the lower end of which extends through the disk 15 which may be soldered, brazed or otherwise attached to the bottom 12 or may be unattached thereto. The

35 upper end of this locking rod or post 14 is longitudinally slotted as at 16, preferably to provide intersecting kerfs. This renders the upper end or head of the rod or post resili- 40 ently compressible and expandable. The upper end of the post is circumferentially grooved to form a shoulder 17 and a head 17^a, this head being upwardly beveled circumferentially or having the form of a truncated cone. The section 11 is formed with

45 the top plate 18 having a coin insertion slot 19 and an observation opening 20.

Extending through this plate or head 18 at the center thereof, is the locking cap 21 which is annular in cross section and provided with an enlarged head which bears against the upper face of the upper plate 18 and may be attached thereto. The central bore 22 of the cap at its lower end is formed with an annular enlargement or circumfer- 50 entially extending recess 23 formed to approximately fit the head 17^a and locking-

engage therewith when the sections of the head spring outward. The bore of this cap is, of course, smaller than the head of the post 14 and the lower corner formed at the junction of this bore with the lower end of the cap is beveled at 24. When the two sections of the bank are telescoped upon each other and the upper end of the post is engaged in the lower end of the cap, the two sections 60 will be locked from longitudinal movement and a key such as shown in Figure 4 and designated generally 25, is inserted for the purpose of unlocking the bank. This key is formed with a shank 26, the lower end of 65 which is hollowed out or recessed at 27 to fit over the beveled upper end of the post and when the key is inserted and depressed, it will force the resilient sections at the upper end of the post inward towards each other, 70 compressing them and withdrawing the head from engagement with the locking recess 23 on the cap. Then the two sections of the bank may be withdrawn from telescopic relation. It will be seen that when the two sections of 75 the bank are engaged with each other and forced towards each other that the beveled end 23 of the bore 22 will engage the conical face of head 17^a and will force the sections of the head inward towards each other, per- 80 mitting the head to pass into the cap and then expand in engagement with the groove 23.

While I have heretofore referred to this lock as being designed for use with coin banks, I 90 do not wish to be limited to such use as it is obvious that the lock might be used in connection with other containers using locks and is not necessarily limited to a container in which the two sections have telescopic en- 95 gagement with each other as the lock could also be used in holding a removable head on one end of the container or might be used with other forms of banks or for any locking purpose.

100 I claim:—

1. A bank formed in two sections, one of said sections carrying a post, the inner end of which is longitudinally split and formed with a circumferentially extending recess to 105 thus define the lower end of a head, said head being conical, the other section of the bank having a tubular locking cap adapted to fit over the post, said locking cap having a central bore less in diameter than the diameter 110 of the head and having a circumferentially extending recess within which the head of the

post is adapted to lockingly engage when the sections of the head are expanded.

2. A bank formed in two sections, one of said sections carrying a post, the inner end of which is longitudinally split and formed with a circumferentially extending recess to thus define the lower end of a head, said head being conical, the other section of the bank having a tubular locking cap adapted to fit over the post, said locking cap having a central bore less in diameter than the diameter of the head and having a circumferentially extending recess within which the head of the post is adapted to lockingly engage when the sections of the head are expanded, and a key adapted for insertion through the cap and having an axial recess at its inner end adapted to engage over the conical head and force the sections thereof defined by said split inward towards each other to thus release it from the cap.

3. A bank formed of two sections having telescopic engagement with each other, each of said sections having a head, one of said heads being formed with a coin insertion slot and a sight opening and at its middle being provided with a tubular cap extending through the head, the bore of the cap at its inner end being circumferentially enlarged and the lower end of the wall of said bore being beveled, the other section of the bank having a post extending upward therefrom, the post being longitudinally split to provide a plurality of resilient sections at the upper end of the post, the upper end of the post being circumferentially recessed to define a head and the head being substantially conical and adapted to fit within the bore of the cap and engage the recess therein, and a key adapted for insertion through the bore of

the cap and having a recess in its lower end adapted to engage the conical face of the upper end of the post and force said sections towards each other to thus release them for the cap.

4. A container having a body and a closure, the body carrying a post, the inner end of which is longitudinally split and formed with a circumferentially extending recess to thus define the lower end of a head, said head being conical, the closure having a tubular locking cap adapted to fit over said head, the locking cap having a central bore less in diameter than the extreme diameter of the head and having a circumferentially extending recess within which the head of the post is adapted to lockingly engage when the sections of the head are expanded.

5. A container having a body and a closure, the body carrying a post, the inner end of which is longitudinally split and formed with a circumferentially extending recess to thus define the lower end of a head, said head being conical, the closure having a tubular locking cap adapted to fit over said head, the locking cap having a central bore less in diameter than the extreme diameter of the head and having a circumferentially extending recess within which the head of the post is adapted to lockingly engage when the sections of the head are expanded, and a key adapted for insertion through the cap and having an axial recess at its inner end adapted to engage over the head and force the sections thereof defined by said split inward towards each other to thus release it from locking engagement with the cap.

In testimony whereof I hereunto affix my signature.

FRED SALINGER.
